Inventor:

Emil Jagsschitz

UNITED STATES PATENT OFFICE.

KONRAD JAGSCHITZ, OF MAINZ, GERMANY, ASSIGNOR TO MASCHINENFABRIK AUGSBURG-NUERNBERG, A. G., OF NUREMBERG, BAVARIA, GERMANY, A CORPORATION OF GERMANY.

GASOMETER.

Application filed July 7, 1923. Serial No. 650,021.

To all whom it may concern:

Be it known that I, KONRAD JAGSCHITZ, a citizen of Austria, and a resident of Mainz, Germany, have invented certain new and useful Improvements in Gasometers, of which the following is a specification.

This invention relates to gasometers and more particularly to that type of gasometers in which the varying gas space is closed by 10 a closing body in the shape of a disc sliding gastight over the inside wall of the gasometer.

The low weight of this type of gasometer which, theoretically would be possible, is in 15 practice, limited by the requirements as to strength and rigidity of the structure itself of the gasometer and of the sliding disc, as also in view of the external strains set up by wind pressure or by the weight of a sheet 20 of snow occasionally resting upon the roof, and of the internal gas pressure, and it is the object of this invention to provide an improved stiffening for such gasometers, in which great rigidity and extreme lightness 25 of weight shall be combined, which shall also allow of a comparatively very light structure of the entire gasometer, and which will therefor enable a considerable saving in the costs of construction and materials.

30 This object of the invention is mainly arrived at by providing either at the top of a gas holder polygonal in cross section, or at both top and bottom, a member of a cross section which will form spatial angles to be 35 enclosed within the vertical walls of the gasometer.

Further objects and advantages of the invention will be apparent from the accompanying drawing which diagrammatically illustrates the invention by way of example.

40 Fig. 1 is a vertical section through the improved gasometer, and

Fig. 2 a horizontal section taken on different planes along the lines 11—11 of Fig. 1.

45 The gas holder 1, upon the inner walls of which the closing disc 2 is adapted to slide up and down, resembles in plan view the shape of a polygon, bounded by a large number of flat or substantially flat vertical 50 panels 1^a, 1^b, 1^c, &c.

At the top, or at both top and bottom of the gas holder 1 stiffening member 3 is arranged which may be constructed either in the shape of a hollow sheet metal body, or as a lattice or girder work, enclosing spatial 55 angles with the vertical panels of the gas holder.

According to the example shown in the drawing the stiffening member is shown to consist of a sheet metal structure at the top 60 of the gas holder, having sides 3^a, 3^b, 3^c, whereas the sliding disc is strengthened by a similar stiffening member formed of a spatial lattice which is likewise denoted by the reference 3^a, 3^b, 3^c, of which the individual 65 girders may be arranged in any known or convenient manner.

In order to further increase the rigidity of the structure the joints between the various panels are made in the shape of angle seams 70 with their edges flanged outwardly so as to form strengthening ribs 4 and which, if desired, may be arranged to enclose additional strengthening members 5.

To give an example of the rigidity of a 75 gasometer strengthened according to the invention it may be stated, that metal plate of a thickness of only four millimeters has proved to be sufficiently strong for a gasometer of 70 meters height and a diameter 80 of 50 meters. Thus very extraordinary savings in the costs of construction and materials may be obtained in comparison to the hitherto usual construction of gasometers.

What I claim is:—

85 In combination, in a disc type gasometer, a gas holder of polygonal cross section and a strengthening member, said member extending inwardly from the walls of the gas holder and having at least some portions of 90 its outer periphery in contact with the interior of the gas holder.

In testimony whereof I affix my signature in presence of two witnesses.

KONRAD JAGSCHITZ.
